ADJUSTABLE REAR SIGHT FOR FIREARMS

George A. Wilson, Hamden, Conn., assignor to
The High Standard Manufacturing Corpora-
tion, New Haven, Conn., a corporation of Con-
necticut

Application February 8, 1945, Serial No. 576,756

4 Claims. (Cl. 33—59)

1

The present invention relates to improvements in rear-sights for firearms and relates more particularly to rear-sights which are adjustable transversely with respect to the firearm-structure to permit the correct alignment of the sights.

One of the objects of the present invention is to provide a superior adjustable rear-sight for firearms in which the adjustment of the sight is readily effected and the locking thereof rendered secure, despite violent shocks and vibration.

Another object of the present invention is to provide a superior adjustable rear-sight embodying adjusting and locking features which will remain fixed against unintentional displacement.

A further object of the present invention is to provide a superior sight of the character referred to which combines ruggedness and durability with ease and low cost of manufacture.

Adjustable rear-sights as heretofore known in the art have been sensitive and delicate in their construction, due mainly to space limitations, and have also been subject to frequent derangement, especially when used on light automatic or semi-automatic firearms which are subject to violent shocks and vibration during their functioning. It is, therefore, a further object of the present invention to provide an adjustable rear-sight which, despite its relative smallness in size, will possess sufficient ruggedness to withstand severe usage.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in rear elevation of an adjustable rear-sight constructed in accordance with the present invention;

Fig. 2 is a view looking toward the right-end thereof;

Fig. 3 is a top or plan view of the rear-sight;

Fig. 4 is a view looking toward the left-end thereof;

Fig. 5 is an underside view of the rear-sight;

Fig. 6 is a transverse sectional view taken on the line 6—6 of Fig. 3 but showing the sight in conjunction with a portion of a firearm upon which the sight may be mounted;

Fig. 7 is a sectional view taken on the line 7—7 of Fig. 6;

Fig. 8 is a perspective view of the clamping-screw, detached;

Fig. 9 is a broken top or plan view of the firearm-element;

Fig. 10 is a perspective view of another form of clamping-screw suitable for use in a sight of the present invention in conjunction with the clamp-
ing-nut of Fig. 11; and

2

Fig. 11 is a perspective view of a modified form of clamping-nut suitable for use in conjunction with the clamping-screw of Fig. 10.

The particular adjustable firearm-sight herein chosen for purposes of illustrating the present invention in Figs. 1 to 9 inclusive, is primarily designed as a rear-sight and comprises a block-like sight-body generally designated by the reference character 15 having its lower-portion shaped in the form of a dovetail mounting-rib 16 which is adapted to fit into a dovetail mounting-groove 17 extending transversely across a firearm-element generally designated by the reference character 18. The said firearm-element may be in the form of the slide of an automatic pistol, the receiver or barrel of a firearm, or any other suitable feature of a firearm-structure upon which it may be desired to mount the adjustable rear-sight of the present invention.

At its rear edge, the sight-body 15 is formed with an integral upwardly-projecting sight-rib 19 extending in parallelism with the mounting-rib 16 before referred to and formed midway of its length with a sight-notch 20.

Adjacent the rear of its mounting-rib 16, the sight-body 15 is formed lengthwise with a cylindrically-contoured clearance-recess 21 extending from its left-end to a point substantially midway of the length of the sight-body and opening through the underside of the mounting-rib 16, as well as through the said right-end of the structure, all as is especially well shown in Figs. 5 and 7. Formed in the portion of the mounting-rib 16 lying intermediate the clearance-recess 21 and the left-end of the sight-body, is an internally-threaded socket 22 extending coaxially with respect to the said clearance-recess 21 but considerably smaller in diameter than the diameter thereof.

For the purpose of providing for the adjustment of the sight-body 15 and the parts carried thereby lengthwise in the mounting-groove 17 of the fire-
arm-element 18, an adjusting screw 23 is em-
ployed. The said adjusting-screw includes a

cylindrical head 24 and an externally-threaded stem 25. The stem 25 is threadedly interfitted in the socket 22 in the sight-body 15, while the head 24 of the said adjusting-screw is accommodated with a close sliding fit in the clearance-recess 21

50 in the said sight-body. Adjacent its inner end, the head 24 of the adjusting-screw 23 is formed with an annular coupling-groove 26 which re-
ceives with a close sliding fit a coupling-rib 27 formed in the bottom-wall of the mounting-
groove 17 of the firearm-element 18, as is es-
pecially well shown in Figs. 7 and 9.

Adjacent its front edge, the sight-body 15 is formed with a longitudinal expansion-slot 28 which extends from a point closely adjacent the 60 right-end of the said sight-body and intersects

the left-end thereof, as is especially well shown in Fig. 5. The upper wall of the said expansion-slot is located but a short distance below the upper-face of the sight-body 15 so as to virtually divide the major part of the lower-portion thereof.

Adjacent its forward left-corner, the sight-body 15 is formed with a vertical unthreaded screw-receiving passage 29 having its longitudinal axis coinciding with but perpendicular to the central-longitudinal axis of the expansion-slot 28 just referred to. The lower-end of the screw-receiving passage 29 is tapered outwardly and downwardly to provide a conically-contoured recess 30 for the reception of a conically-contoured head 31 formed at the lower-end of a clamping-screw generally designated by the reference character 32.

Located axially with respect to the screw-receiving passage 29 but in the upper-portion of the sight-body 15, is a cylindrical recess 33 in which is located a clamping-nut 34 having a diametric kerf 35 in its upper face. The said nut is cylindrically contoured externally to fit the recess 33 and threadedly engages with the upper end of the clamping-screw 32, as is especially well shown in Fig. 6.

To guard against the unintentional turning movement of the clamping-screw 32 when the clamping-nut 34 is turned with respect thereto, the conical head 31 of the said clamping-screw is provided at diametrically-opposite points respectively with one of two anchoring-ribs 36 and 37 both adapted to fit within the adjacent portions of the expansion-slot 28 in the sight-body 15, to thus hold the said clamping-screw 32 against turning movement relative to the sight-body.

To install the rear-sight above described in the mounting-groove 17 or its equivalent of the firearm-element 18, the adjusting-screw 23 should first be unscrewed and removed from the sight-body 15 and placed in the bottom of the dovetail mounting-groove 17 so that the coupling-groove 26 thereof fits over the coupling-rib 27 in the bottom of the said mounting-groove 17. The clamping-nut 34 should be loosened so as to thereby permit the conical head 31 of the clamping-screw 32 to move slightly downwardly, to thereby permit the metal on the respective opposite sides of the expansion-slot 28 to spring back slightly toward each other to a degree sufficient to permit the dovetail mounting-rib 16 to be readily inserted into the left side of the dovetail mounting-groove 17 in the firearm-element 18 with its clearance-recess 21 foremost.

The sight-body, together with the parts carried thereby, is moved from left to right into the mounting-groove 17 until the end of the threaded stem 25 of the adjusting-screw 23 enters into threaded engagement with the threaded socket 22 in the sight-body 15. Once threaded engagement has been effected between the stem 25 and the socket 22, the sight-body may be drawn from left to right by turning the adjusting-screw 23. During this operation, the projection of the coupling-rib 27 into the annular coupling-groove 26 in the adjusting-screw 23 will serve to hold the said adjusting-screw against axial movement while permitting the free rotation thereof.

When the sight-body has been shifted lengthwise of itself to the desired point by means of the adjusting-screw 23, the said sight-body and the parts carried thereby may be locked in the selected position by tightening the clamping-nut 75

34. The tightening of the clamping-nut 34 will draw upwardly upon the clamping-screw 32 and thereby cause the conical head 31 thereof to act against the surfaces of the conical recess 30 in the sight-body 15 to spread the dovetail mounting-rib 16 into very tight frictional engagement with the respective front and rear walls of the dovetail mounting-groove 17 in the firearm-element 18. This latter action will firmly lock the said sight-body 15 and the parts carried thereby in the selected position of adjustment.

The sight-body 15 may be released, readjusted and relocked repeatedly without occasioning any mutilation of the parts and with assurance that the newly-selected position of adjustment will be maintained, despite the violence of shocks and vibration to which the assembly may be subjected.

Instead of employing the clamping-screw 32 and the clamping-nut 34, a clamping-screw 38 and a clamping-nut 39 respectively shown in Figs. 10 and 11, may be employed. The said clamping-screw includes a head 40 adapted to fit into the recess 33 and a threaded stem 41 adapted to extend downwardly through the screw-receiving passage 29. The clamping-nut 39 is conically-contoured to fit the recess 30 and is internally threaded to receive the lower end of the stem 41. The clamping-nut 39 is also provided with anchoring-ribs 42 and 43 which are adapted to enter the expansion-slot 28 to hold the said clamping-nut against turning movement.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable rear-sight for firearms, including in combination: a sight-body provided at its upper-portion with sighting-means and provided at its lower-portion with a mounting-rib extending at substantially a right angle with respect to the axis of the said sighting-means and constructed and arranged for entry into a mounting-groove in a firearm-element, the said sight-body being formed in its said mounting-rib with a substantially-vertical downwardly-opening expansion-slot which also extends in substantial parallelism with the length of the said mounting-rib, the said sight-body also being formed with a substantially-vertical screw-receiving passage intersecting the said expansion-slot and formed in its lower-portion with a conically-contoured recess; substantially-vertical clamping-screw means mounted in the screw-receiving passage in the said sight-body and having a conically-contoured lower-portion engaging with the conically-contoured recess in the lower-portion of the said screw-receiving passage to laterally expand the mounting-rib of the said sight-body along the said expansion-slot and into firm locking engagement with the walls of a mounting-groove in a firearm-element; and an anchoring-projection formed on the said clamping-screw means and entering the expansion-slot in the sight-body to hold the conically-contoured portion of the said clamping-screw means against rotation with respect to the sight-body.

2. An adjustable rear-sight for firearms, including in combination: a sight-body provided at

2,465,561

5

its upper-portion with sighting-means and provided at its lower-portion with a mounting-rib extending at substantially a right angle with respect to the axis of the said sighting-means and constructed and arranged for entry into a mounting-groove in a firearm-element, the said sight-body being formed in its said mounting-rib with a substantially-vertical downwardly-opening expansion-slot which also extends in substantial parallelism with the length of the said mounting-rib, the said sight-body also being formed with a substantially-vertical screw-receiving passage intersecting the said expansion-slot and formed in its lower-portion with a downwardly-and-outwardly - tapering conically - contoured recess; substantially-vertical clamping-screw means mounted in the screw-receiving passage in the said sight-body and having a downwardly-and-outwardly - tapering conically - contoured lower-portion engaging with the downwardly-and-outwardly-tapering conically - contoured recess in the lower-portion of the said screw-receiving passage to laterally expand the mounting-rib of the said sight-body along the said expansion-slot and into firm locking engagement with the walls of a mounting-groove in a firearm-element; and an anchoring-projection formed on the said clamping-screw means and entering the expansion-slot in the sight-body to hold the conically-contoured portion of the said clamping-screw means against rotation with respect to the sight-body.

3. An adjustable rear-sight for firearms, including in combination: a sight-body provided at its upper-portion with sighting-means and provided at its lower-portion with a mounting-rib extending at substantially a right angle with respect to the axis of the said sighting-means and constructed and arranged for entry into a mounting-groove in a firearm-element, the said sight-body being formed in its said mounting-rib with a substantially-vertical downwardly-opening expansion-slot which also extends in substantial parallelism with the length of the said mounting-rib, the said sight-body also being formed with a substantially-vertical screw-receiving passage intersecting the said expansion-slot and formed in its lower-portion with a tapered recess and in its

6

upper-portion with a second recess; a clamping-screw having a tapered head fitting the tapered recess at the lower-end of the screw-receiving passage in the said sight-body, the said clamping-screw also having a stem extending upwardly through the said screw-receiving passage; and a clamping-nut threadedly engaged with the stem of the said clamping-screw and located in the recess at the upper-portion of the screw-receiving passage in the said sight-body.

4. An adjustable rear-sight for firearms, including in combination: a sight-body provided at its upper-portion with sighting-means and provided at its lower-portion with a mounting-rib extending at substantially a right angle with respect to the axis of the said sighting-means and constructed and arranged for entry into a mounting-groove in a firearm-element, the said sight-body being formed in its said mounting-rib with a substantially-vertical downwardly-opening expansion-slot which also extends in substantial parallelism with the length of the said mounting-rib, the said sight-body also being formed with a substantially-vertical screw-receiving passage intersecting the said expansion-slot and formed in its lower-portion with a tapered recess and in its upper-portion with a second recess; a substantially-vertical clamping-screw having a head seated in the recess in the upper-portion of the said screw-receiving passage and having a stem extending downwardly through the latter; and a tapered clamping-nut seated in the tapered lower-portion of the screw-receiving passage in the sight-body and threadedly engaged by the stem of the said clamping-screw.
